UNITED STATES PATENT OFFICE.

WILLIAM T. BENHAM, OF RISING SUN, INDIANA.

DIAL FOR COMBINATION-LOCKS.

1,156,658.

Specification of Letters Patent. Patented Oct. 12, 1915.

Application filed January 5, 1914. Serial No. 810,353.

To all whom it may concern:

Be it known that I, WILLIAM T. BENHAM, a citizen of the United States, residing at Rising Sun, in the county of Ohio and State of Indiana, have invented new and useful Improvements in Dials for Combination-Locks, of which the following is a specification.

My improvements relate to dials for combination locks, such as are ordinarily used on safes, vaults and the like.

My improvements are intended to simplify and make more certain the running of the combination, so that such locks will be more widely used, as on doors of buildings.

My improvements consist fundamentally of a combination lock dial with its periphery notched, one notch for each number of the count, and bored at the tens, one hole for each ten numbers of the count; a plunger to contact with the holes at will and an operating ratchet-pawl or its equivalent to contact with notches and turn the dial in either direction desired.

While the dial may be numbered only one way, as is common practice now, it will be more convenient to number it both ways from zero, as disclosed in my prior Patent No. 1,113,865, dated October 13, 1914.

If the operator is nervous or in a hurry he frequently finds it hard to turn the dial to the exact number desired without passing the number. Such mistakes make it necessary to rerun the entire combination. My invention insures the absolute accuracy desired. Such a device can also be run with accuracy in the dark, as will appear from the description.

In the particular embodiment of my invention selected for illustration in the accompanying drawings: Figure 1 is a front elevation of a safe dial with notched and bored periphery and dial rim fitted with plunger and ratchet-pawl devices, one of such devices having the front cover of its casing frame removed; Fig. 2 is an enlarged detail of the pawl frame; Fig. 3 is an enlarged detail of the pawl; Fig. 4, a detail, is an edgewise elevation of the dial; and Fig. 5 is a dial and rim with an alternative form of ratchet-pawl device.

Referring now to the drawings, A is the dial and B the dial rim. The dial is of the usual rotating sort except the graduations are numbered both clock-wise and counter-clock-wise from zero, and at each unit grad-

uation is a notch a, in the periphery. The handle a¹ is set at zero, and the plunger b is set at the point on the rim where the count is started, so whether the dial is in the light or not, it would be easy for the operator to find the starting point and to know when zero passed it in any count.

The front of the dial periphery is undercut, as shown in Fig. 4, and groups of lock combination units herein shown in the form of holes a² are so bored as to contact with the plunger b when it is depressed by pressure upon the head b¹. The plunger b is held normally out of contact with the holes by a spring b².

On each side of the rim, and seated in slots in it, are pawl devices R, consisting of a slidable frame r with a recess r¹ to receive a stud b³ in the rim to limit the sliding motion of the frame; a lengthwise recess r² on the inner front side, as a seat for the pawl r⁴; a stud r⁵ adapted to fit in the hole r⁶ of the pawl, and act as a pivot, and a hole r⁷ adapted to receive a spring r⁸ which seats upon the underside of the lateral extension r¹⁰, constituting a lever handle for the operation of the pawl in and out of engagement with the dial notches. The pawl is undercut at r⁹ to permit the outward movement of its top portion while rotating on the pivot r⁵. A plunger b⁴ seated in a hole b⁵ in the dial rim B presses against the lower end r⁹ of the pawl frame r because of the spring b⁶. A plate B¹ forms a cover for the pawl mechanism and holds it in place.

The pawl-device on the right side of the dial must be used when it is desired to rotate the dial toward the right with a pawl, and the corresponding device on the left side must be used when it is desired to rotate the dial toward the left with such a pawl.

In the alternative form of ratchet-pawl device shown in Fig. 5, a pinion c fixed to the pilot wheel c¹ has its shaft c² journaled in the dial rim at the back and the cover plate B² at the front. The cover plate B² and the rim B are cut out below just enough to permit the finger to enter at either side of one of the handles c³ of the pilot wheel, so that the operator can turn the wheel and pinion just one notch or unit count in the direction desired at one time.

The dial thus provided is operated in the following manner: Grasp the handle a¹ and turn the dial to the point next to b on the rim where the count is started, the exact

point may be found by pressing down on the plunger-head b^1 , then rotate the dial in the desired direction as many full turns past the starting point as the combination number requires, and on in the same direction as many tens, determined by pressure on b^1 , as required, then press down on the appropriate ratchet-pawl lever r^{10} as many times as there are units to complete that count. Pressure 10 on the lever r^{10} depresses it, throwing the pawl point r^{11} into contact with the notches a on the dial periphery. The ratchet-pawl mechanism is so placed that this initial action of the pawl will throw the point r^{11} into 15 a notch. Further downward pressure on the lever carries the ratchet pawl r^4 and pawl frame r downward in its slide the distance of one notch a , as limited by the length of the recess r^1 . Release of pressure on r^{10} 20 allows the spring b^6 to bring the ratchet mechanism back into place ready for the next notch.

When the alternative form of pawl device shown in Fig. 5 is used, the finger contacting with the spur c^3 of the pilot-wheel c^1 and pressing it to the desired side as far as the cover plate B^2 will allow, the same result is attained as by use of the pawl in the form 25 shown in Fig. 1.

30 I claim as my invention and desire to secure by Letters Patent of the United States:

1. In a combination lock having a rotatable dial and a fixed rim, a circular notched rack on the dial, such notches constituting a unit gage for running the combination of the lock to which the dial is applied; said dial having, also, groups of lock combination units; means upon the fixed rim adapted to rotate the dial in either direction by contact with the notches of the rack, and a plunger upon the fixed rim normally out of contact with the groups of lock combination units but adapted to be contacted with them at will.

2. A rotatable dial for combination locks, having a fixed rim, a circular notched rack on the dial, such notches constituting a unit gage for running the combination of the lock to which the dial is to be applied, holes in the dial, such holes constituting a gage for groups of lock combination units, a pawl upon the rim adapted to rotate the dial by contact with the notches of the rack, and a plunger upon the rim adapted to be contacted with the holes in the dial at will.

In testimony whereof I have hereunto set my hand in presence of two subscribing witnesses.

WILLIAM T. BENHAM.
